UNITED STATES PATENT OFFICE.

EDWARD A. SLYE, OF HARTFORD, CONNECTICUT, ASSIGNOR TO THE VEEDER MANUFACTURING COMPANY, OF HARTFORD, CONNECTICUT, A CORPORATION OF CONNECTICUT.

COMPENSATING DEVICE FOR OIL-PUMP COUNTERS, ETC.

Application filed February 21, 1924. Serial No. 694,235.

To all whom it may concern:

Be it known that I, EDWARD A. SLYE, a citizen of the United States, residing in Hartford, in the State of Connecticut, have 5 made certain new and useful Improvements in Compensating Devices for Oil-Pump Counters, Etc., of which the following is a specification, reference being had to the accompanying drawings, forming a part 10 hereof.

In the applications of Harold J. Williams, Serial No. 679,918, and of Curtis Hussey Veeder, Serial No. 679,919, both filed December 11, 1923, and both assigned to the 15 assignee herein, there are shown and described devices for compensating the movement of counters for gasoline pumps designed to compensate the movement of the counting mechanism for variations in the 20 delivery of different pumps of the same manufacture, such devices being of such a character that the compensation is proportional to the length of stroke of the pump. In the devices covered by such applications, 25 compensation proportional to the length of stroke of the pump is dependent upon the fact that one of the members of the compensating device has not only a rotary oscillating movement but also a longitudinal 30 movement or a movement of displacement during and with respect to its rotary oscillating movement, so that the compensation is progressive during the stroke of the pump and is proportional to the length of stroke 35 of the pump. In the development of the inventions covered by said applications, it has been found that compensation proportional to the length of stroke of the pump can be attained by mechanism which is different in character from that described in 40 said applications and under some conditions of use may be considered preferable. Such other mechanism will be described herein- 45 after with reference to the accompanying drawings in which it is illustrated and in which—

Figure 1 is a view in front elevation of a dial counting mechanism in connection with which the present improved compensating devices may be employed, the dial plate being partly broken away and the casing 50 being shown partly in section.

Figure 2 is a view in section on the plane indicated by the broken line 2—2 of Fig-

ure 1, looking in the direction of the arrows. 55

Figure 3 is a view in section on the plane indicated by the broken line 3—3 of Figure 1, looking in the direction of the arrows.

Figure 4 is a detail view, partly in section and partly in elevation, illustrating 60 particularly the connection from the gear segment through the clutch mechanism to the driven part.

Figures 5 and 6 are detail views in elevation of the compensating devices, with 65 parts shown in different positions in the several figures.

Figure 7 is a detail view of the resetting gears.

In the embodiment of the invention illustrated in the drawings, the several working parts, including the dial *a*, the pointer *a'*, the pointer supporting shaft *a*² and the totalizing counter *a*³ are supported by a suitable cast metal frame or casing *b* and bridge piece *b'*, the latter supporting a bearing sleeve *b*² in which the shaft *a*² is mounted as hereinafter explained. The counting mechanism is actuated in the operation of the pump, through a lever *c* in operative 75 engagement with a moving part of the pump mechanism, not necessary to be shown, preferably the shaft or gear by which the rack bar of the pump is actuated, the lever *c* being secured to a shaft *c'* which carries a pinion *c*² in engagement with a gear segment *d* which receives, through the forward and reverse movements of the pinion *c*², a rotary oscillating movement. The gear segment *d* is shown as supported upon the 80 sleeve *b*², which is carried by the frame member *b'*. The arm *d'* of the gear segment supports pivotally at *d*², a lever *e* which is forked at its upper end, as at *e'* (see Figures 2 and 6) to straddle an adjustable fulcrum block *f* which is carried by a lever *f'* pivoted on the main frame or casing, as at *f*². At its other extremity the lever *f'* is slotted longitudinally, as at *f*³, to engage an eccentric pin *f*⁴ carried by a short 85 shaft *f*⁵ which is mounted in a clamping bearing *b*⁵ supported by the main frame or casing *b*. The shaft *f*⁵ may be engaged, outside of the casing, by a suitable key or instrument, indicated by broken lines in Figure 3, for the purpose of rotating the shaft *f*⁵ and so changing the position of the eccentric pin *f*⁴ and, through the lever *f*,

shifting the position of the fulcrum block f . Thereby the fulcrum block f may be shifted from its normal, mediate position shown in Figure 1, either toward its highest position, shown in Figure 5, for a long stroke of the pump, or toward its lowest position, shown in Figure 6, for a short stroke. As the lever e is supported by and oscillates with the segment d , it is obvious that the lower end of the lever e will oscillate through an arc which is least when the fulcrum is in its highest position, as shown in Figure 5, and is greatest when the fulcrum is in its lowest position, as shown in Figure 6. Through a link e^2 at its lower end the lever e engages operatively a lever g , mounted concentrically with the shaft a^2 . The lever g is operatively connected with the counting mechanism, as hereinafter described, and is the driven member of the compensating devices. It will be obvious that when the fulcrum block f is in its median position, the angular motion of the lever g is the same as that of the segment d . When the stroke of the pump, necessary to deliver a unit volume of liquid, is shorter than the standard stroke, so that the gear segment d is moved through an angle somewhat less than its normal movement of about 90° , it is obvious that in order to register upon the counting mechanism the delivery of a unit volume of liquid, the angular motion of the lever g , must be greater than that of the gear segment d . Consequently, for a pump stroke shorter than the standard, the fulcrum block f must be lowered, as shown in Figure 5. On the other hand, if the stroke of the pump necessary to deliver a unit volume of liquid is greater than the standard stroke, so that the gear segment d moves through an angle somewhat greater than its normal movement of about 90° , the movement of the actuating lever g , must be less than that of the gear segment. Consequently, for a pump stroke longer than the standard, the fulcrum must be raised, as shown in Figure 6, so that, notwithstanding the longer stroke of the pump the counting mechanism shall register only the delivery of a unit volume of liquid.

As a means for actuating the counting mechanism from the lever g , in the embodiment of the invention illustrated in the drawings, the lever g is operatively connected through a friction ball clutch g^2 of ordinary construction with a flanged disc h which is fixed on a sleeve h' mounted in the bearing member b^2 and receiving within itself the shaft a^2 . A retaining clutch g^3 , supported by a frame member b^3 , is provided to prevent backward movement of the flanged disc h . Secured to the sleeve h' is a gear h^2 which meshes with a gear a^4 of the totalizing counter a^3 , to drive the same in

any usual manner, the totalizing counter being of any suitable or preferred construction.

The pointer a' is connected with the shaft a^2 through a frictional connection indicated at a^5 , so that in the resetting operation, to be explained, the pointer may come to rest against the stop a^6 on the dial plate a . For the purpose of resetting the pointer to its initial position after each operation the shaft a^2 , at its further end, is provided with a gear i , preferably having unsymmetrical teeth as shown in Figure 7, to prevent locking, the gear i being adapted to be engaged, in the resetting operation, by a multilobed gear i' fixed on a sleeve i^3 (see Figure 3) which is mounted on a stud b^4 , supported by the frame member b' . The sleeve i^3 is provided with a ratchet wheel i^4 , engaged by a pawl i^5 (see Figure 1), to prevent reverse movement of the multilobed resetting gear i' . The sleeve i^3 also carries or has formed therewith a bevel gear i^6 , engaged by a bevel gear i^7 on the resetting shaft i^8 . It is necessary that the multilobed gear i' be retained in a fixed position during the operation of the counter so that the teeth of the gear i will not interfere with those of the gear i' . The gear i' is rotated through the bevel gears i^6 and i^7 from the resetting shaft i^8 . The hub of the gear i^7 , which is mounted loosely on the shaft i^8 is slotted for engagement with a pin i^9 carried by the shaft i^8 and a spring i^{10} , acting against a shoulder of the shaft i^8 , presses the shaft normally outward, the pin i^9 being, however, always in engagement with the slotted hub of the gear i^7 . In the shaft i^8 , near the outer end, is fixed a pin i^{11} which, in the normal position of the shaft, engages a notched plate i^{12} , to hold the shaft from rotation and thereby to hold the gear i' from rotation. When the resetting operation is to be performed, the shaft i^8 is pressed inward thereby disengaging the pin i^{11} from the notched plate i^{12} and freeing the shaft i^8 for rotation. The gear i^7 is twice the diameter of the gear i^6 so that a half rotation of the shaft i^8 effects a complete rotation of the gear i^6 , whereby the gear i' is actuated to effect the resetting of the counter. At the close of the half rotation of the shaft i^8 the pin i^{11} is brought into engagement with the diametrically opposite slot of the plate i^{12} and the shaft is again held in fixed position. The action of the spring i^{10} maintains the gear i^7 always in engagement with the gear i^6 . At each operation of discharging gasoline or other liquid, up to the limit of the apparatus, the total counter is driven forward and after each such operation the pointer is reset to its zero or initial position.

It will be understood that the compensating devices herein described can be applied

to the operation of counting mechanisms of different construction from that indicated and can be varied in details of construction and arrangement to suit different conditions 5 of use. Except as pointed out in the claims, therefore, the invention is not limited to the particular construction shown and described herein.

I claim as my invention:

- 10 1. The combination of a counting mechanism for a pump, a continuously oscillating lever actuated with the pump, an adjustable fulcrum block for said lever, a second oscillating lever in operative relation with the counting mechanism, and means whereby the said second lever is oscillated by the other lever.
- 15 2. The combination of a counting mechanism for a pump, a continuously oscillating lever actuated with the pump, a second oscillating lever in operative relation with the counting mechanism, means whereby the said second lever is oscillated by the other lever, and means including an adjustable fulcrum block for the first lever to vary the angular movement of the second lever with respect to the other lever.
- 20 3. The combination of a counting mechanism for a pump, an oscillating lever actuated with the pump, a second lever pivotally mounted on the first, and a third lever operatively connected to the counting mechanism and in operative engagement with the second lever to be oscillated thereby.
- 25 4. The combination of a counting mechanism for a pump, an oscillating lever actuated with the pump, a second lever pivotally mounted on the first, a third lever op-

eratively connected to the counting mechanism and in operative engagement with the 40 second lever to be oscillated thereby, and means to shift the fulcrum of the second lever to vary the angular movement of the third lever.

5. The combination of a counting mechanism for a pump, a pinion actuated with the pump, a gear segment in engagement with the pinion, a lever pivotally mounted on the gear segment, and another lever operatively connected to the counting mechanism and in 50 operative engagement with the first mentioned lever to be actuated thereby.

6. The combination of a counting mechanism for a pump, a pinion actuated with the pump, a gear segment in engagement with 55 the pinion, a lever pivotally mounted on the gear segment, another lever operatively connected to the counting mechanism and in operative engagement with the first mentioned lever to be actuated thereby, and 60 means to shift the fulcrum of the first mentioned lever to vary the angular movement of the second mentioned lever.

7. The combination of a counting mechanism for a pump, an oscillating lever actuated with the pump, a second lever pivotally mounted on the first, a third lever in operative engagement with the second lever to be actuated thereby, and operative connections between the second lever and the 70 third lever, said connections including a friction clutch.

This specification signed this 19 day of February A. D. 1924.

EDWARD A. SLYE.
